UNITED STATES PATENT OFFICE.

CURTIS W. SHIELDS, OF BROOKLYN, NEW YORK, ASSIGNOR TO UNDERWOOD TYPE-WRITER COMPANY, OF NEW YORK, N. Y., A CORPORATION OF DELAWARE.

TYPE-WRITING MACHINE.

1,276,275.

Specification of Letters Patent. Patented Aug. 20, 1918.

Application filed June 26, 1916. Serial No. 105,792.

To all whom it may concern:

Be it known that I, CURTIS W. SHIELDS, a citizen of the United States, residing in Brooklyn borough, in the county of Kings, 5 city and State of New York, have invented certain new and useful Improvements in Type-Writing Machines, of which the following is a specification.

This invention relates to means for use 10 with typewriting machines, to facilitate a quick and accurate adjustment of work-sheets on the platen in position for being written upon, particularly where such sheets are placed on the machine a number of 15 times, the sheet being adjusted at each new insertion to a different or more advanced position, corresponding to the increase in the typewritten matter thereon.

The invention is also advantageous for use 20 in work in which a number of the sheets are placed on the machine together in different positions of advancement, and especially where one or more of said sheets are repeatedly placed on the machine, each time 25 in a different position relatively to other sheets collated therewith, as is customary for example, in some systems of book-keeping.

An object of the invention is to provide 30 means, operative upon a work-sheet while the latter is on the machine, to produce an impression on the sheet which will later serve as a gage in adjusting the sheet on the platen. Such impression may be made at a 35 position corresponding to the advancement of the sheet in line-spacing direction, at the completion of the typewritten matter, before the sheet is removed, so that when the sheet is again placed on the machine to be further 40 written upon, it may be quickly and accurately adjusted by means of said impression, to a position corresponding to the position of the last typewritten line.

More specifically, the invention may comprise 45 a cutting or punching device or devices operable as the work-sheet is advanced around the platen, to shear or punch portions of the sheet along the side edges, thereby leaving upon the edges of the work-sheet 50 gaging surfaces or shoulders at positions corresponding to the advancement of the sheet, said cutting devices themselves preferably serving as gages, so that the sheet,

after it has been removed from the machine, 55 may again be placed thereon and gaged or brought to the position it occupied before it was last removed. The combined cutting and gaging devices may be located, one at each end of the roller platen and arranged to be operated by the usual line-spacing 60 mechanism to cut or trim off a section of each side margin of the work-sheet at each line-spacing operation. A narrow strip of waste may thus be trimmed off each side margin little by little as the page is written. 65 This operation leaves shoulders or jogs in the sheet at the termination of the trimmed-off portions. Hence, each sheet has opposite shoulders on its side edges at positions therealong corresponding to the position of the 70 last typewritten line. These shoulders are naturally in engagement with the ends of the punches, and the latter thus form gages so that, when a sheet has been removed from the machine and later replaced to receive 75 further typewritten matter, it may be drawn forwardly until the shoulders abut against the punches or gages, whereupon the usual feed rolls may clamp the sheet against the platen in the exact position occupied when 80 last operated upon by the cutting devices, before it was taken from the machine.

When a number of sheets have been placed on the machine and written upon, the under sheet may be allowed to remain in the machine while a fresh top sheet is substituted, 85 having jogs or shoulders whereby it can be set immediately to position to write the next line thereon. This top sheet may have been partly written before, so that it is provided 90 with alining shoulders or jogs. Said sheets may also be manufactured with their upper edges trimmed off to form gaging shoulders which, when adjusted to the punching gages, 95 position the sheet for the first line of writing.

The sheet-gaging cutters or punches may be arranged to be operated by the usual line-spacing lever. The latter has an initial movement during which the platen remains 100 at rest, while the cutters are swung to cutting and gaging position, and then released and swung out of the path of the work-sheets before the latter are advanced by the line-spacing mechanism. A key may be 105 provided to silence the cutting and gaging

devices. Said devices may also be controlled by the usual platen-feed-roll release key which, when depressed to move the feed rolls off the platen, also sets the gages to operative position, so that when a sheet or sheets are placed on the platen, they may be drawn forward until arrested by said gages, in position to be written upon. The feed-roll release key may then be returned, thereby causing the feed rolls to clamp the sheet in position on the platen and cause the gaging devices to be withdrawn.

A key may be provided to actuate the cutting gages independently of the line-spacing mechanism and the feed-roll release key.

Other features and advantages will hereinafter appear.

In the accompanying drawings,

Figure 1 is a perspective view showing the carriage of an Underwood typewriting machine with the present invention applied thereto.

Fig. 2 is a sectional elevation showing the mechanism at the left-hand end of the platen, the parts being in their normal position of rest.

Fig. 3 is a part sectional front elevation view of the same mechanism.

Fig. 4 is a sectional view showing a cutting gage at the finish of its cutting stroke during the operation of the line-spacing lever, before the latter has operated to rotate the platen.

Fig. 5 shows a cutting gage as operated by the platen-feed-roll release key, the latter being shown depressed, the feed rolls off the platen, and the gage held in operative position.

Fig. 6 is a perspective view showing the method of adjusting the work-sheets to the gages.

Fig. 7 is a fragmentary view of a work-sheet with its margin formed with a gaging shoulder.

Fig. 8 illustrates the position of a gage and its operating parts at the completion of the operating stroke of the line-spacing lever, the gage having been operated thereby and returned to normal inoperative position before the line-space lever has returned.

Fig. 9 shows the platen-feed-roll release key depressed to a point where the feed rolls are thrown off the platen thereby, but not depressed far enough to operate the cutting gage.

Fig. 10 is a view showing the silencing key for the gages depressed, permitting the line-spacing mechanism to operate without operating the gages.

Fig. 11 is a sectional view as indicated by the section line 11-11 on Fig. 2.

A rotary platen 12 may be fixed to the platen axle 13 journaled in the ends 14 and 15 of a platen frame. An inclined paper-shelf 16 at the introductory side of the platen

may form part of the platen frame. Type-bars 17 (Fig. 2) may be operated by the usual mechanism, to cause the types thereon to strike against the front face of the platen. The platen frame and platen may be shiftable to upper and lower-case positions on the carriage frame 18. The carriage may be mounted on the machine frame for letter-feed travel, the usual mechanism for driving the carriage and controlling its letter-feed movements being provided. The platen may be rotated either by hand-wheels 19 secured to the ends of the platen axle, or by means of the usual line-spacing mechanism. Such mechanism comprises the line-spacing lever 20 pivoted on the carriage and having an arm 21 which, when the lever is operated, moves rearwardly a slide bar or driver 22 on which is pivotally mounted a dog 23 to engage and drive a line-space ratchet wheel 24 fixed to the platen, and thereby rotate the platen. The line-spacing lever and said driver may be returned by a spring 25. The stroke of the line-spacing pawl is regulatable as usual for 1, 2 or 3 spaces by a handle 20a.

The work-sheets may be placed on the paper-shelf 16 and advanced around the under side of the platen, and upwardly over the front face of the platen to writing position, being guided between the platen and a guide plate 26 forming a continuation of the shelf 16.

Platen feed rolls 27 and 28 normally bear upon the under surface of the platen and coöperate therewith to feed the work-sheets as the platen is rotated. Said feed rolls may be thrown off the platen to permit the work-sheets to be adjusted on the platen or removed while the platen is at rest. For this purpose, a feed-roll release key 29 is pivoted at 30 on the platen frame, and comprises an arm 31 connected through a link 32 to a rock arm 33 on a rock shaft 34. The feed rolls are mounted on shafts 35 supported in levers 36 pivoted on a rod 37, said levers comprising arms 38 which may be spread by means of flats or cams 39 on the rock shaft 34. Thus when the key 29 is depressed to the Fig. 5 position, the feed rolls 27 and 28 are thrown off the platen and held in such position until an upward pressure is applied to the key 29 to restore said rolls to the platen, where they are held by springs (not shown). The parts thus far described may be of the usual construction found in commercial Underwood typewriting machines.

The mechanism for operating on the work-sheets to provide gaging means thereon, will now be described. Such mechanism may comprise cutters or punching devices 40 at opposite ends of the platen, which may operate, at each operation of the line-spacing mechanism, to punch or cut a section of a 130

narrow strip off each side edge of the work-sheets on the platen, the length of each section or cutting being of course equal to a line-space distance, or the distance the work-sheets is advanced by an operation of the line-space lever. By this operation shoulders or 5 gaging edges 41 are formed on the margins of the work-sheets, such gaging shoulders thus always having a fixed relation to the 10 last typewritten line on the work-sheet.

The cutting devices 40 serve as gages to which the gaging edges 41 may be adjusted, so that if a work-sheet has been written upon by the machine and then removed, the 15 gaging shoulders 41 formed during the line-spacing operations, provide a means by which the sheets may be quickly and accurately adjusted, when again placed on the machine, to a position determined by the 20 position of the last typewritten line upon the sheet.

The cutters or punches 40 are each mounted on a rock arm 42, said arms being fixed to a rock shaft 43 which may be journaled 25 in the ends of the platen frame. The shaft 43 may be rocked by means hereinafter described, to swing the punches or dies 40 downwardly into die-openings 44 formed in die-plates 45, each of which may be in the 30 form of a ring mounted on an annular flange or projection 46 formed on a supporting plate 14^a attached to the adjacent platen frame end and projecting inwardly from said plate toward the platen. The rings 45 35 may be of the same diameter as the platen 12 and concentric therewith, said rings abutting against the ends of the platen and forming a supporting surface or backing for the margins of the work-sheets which 40 project beyond the end of the platen. Each ring 45 may be secured to its supporting annular flange 46 by clamping screws 47, which extend freely through openings 48 in the ring 45 and are threaded into the flange 46. 45 The openings 48 may be elongated to permit rotative adjustment of the said ring to accurately register the die-opening 44 with the cutter 40.

The mechanism through which the line-space lever is operative to actuate the cutters, will now be described. The forward end 49 of the slide bar 22, which is bent inwardly to extend perpendicular to the body of said bar, thereby providing a shoulder 50 against which the arm 21 bears, is utilized to actuate the cutters. For this purpose, an arm 50 (Figs. 2, 4 and 8) connected by a pivot 51 to a rock arm 52 on the shaft 43, extends forwardly from its pivot, with its 55 forward end supported directly behind the end 49 of the slide bar 22 to be actuated thereby. The cutters 40 are normally held up in the Fig. 2 position by means of a coil spring 53 (Fig. 1) on the rock shaft 43, one 60 end of said spring being connected to the rock shaft, and the other end of the spring anchored in the platen frame end. There is thus provided a passageway between the rings 45 and the said cutters through which the side margins of the work-sheets may 70 extend.

When the line-spacing lever 20 is moved to the right for a line-spacing operation, the slide bar 22 is moved rearwardly, and has a limited idle movement before the dog 23 engages the line-space wheel to rotate the platen. This idle or lost motion is utilized to actuate the cutters 40, as it is obviously desirable that the cutting or punching operation should be effected and the cutters 80 withdrawn from the path of the work-sheet while the platen is still at rest.

As shown in Fig. 2, the end 49 of the slide bar 22 is directly in front of the forward end of the arm 50, so that as said slide bar moves rearwardly from its starting position 49^b, Fig. 4, to the full-line position, the arm 50 is also moved rearwardly and operates through the arm 52 to rock the shaft 43 and swing the cutters inwardly, 90 thereby cutting a section off each side margin of the work-sheet. The parts are so timed that the cutters 40 have completed their operative stroke by the time the line-spacing pawl 23 has been brought to position to drive the ratchet wheel. In order to release the arm 50 from the driver 49 at or before this time, said arm 50 is provided with a forwardly and upwardly inclined cam surface 55 beneath a pin 56 on the 100 platen frame. As the arm 50 is moved rearwardly, it is at the same time cammed downwardly by said pin, and as it reaches the Fig. 4 position is disengaged from the driver 49, permitting the latter to continue 105 its forward movement to the 49^a position, thereby line-spacing the platen, while, the arm 50 being released, the spring 53 throws the cutters back to starting position. When the driver 49 is returned to its initial position 49^b (Fig. 4), the arm 50 is thrown upwardly to the Fig. 2 position, by means of a leaf-spring 57. Said spring 57 is connected 110 with a swinging arm or latch 58, connected by a pivot 59 with the arm 50. Said arm 50 is held with a yielding pressure against the pin 56 by means of the spring 57, the forward end of which is supported on a pin 60 in the arm 50.

The operation of the cutting device, in 120 conjunction with the line-spacing operation, may be briefly reviewed as follows: When the line-space lever is operated, the movement of the driver thereby from the starting position 49^b (Fig. 4) to the full-line position (Fig. 4), swings the cutters 40 inwardly, causing each cutter to sever from the margin of the work-sheet a strip equal in length to a line-space distance. As the driver 49 reaches the full-line position (Fig. 125 130

4), the arm 50 is carried below the driver, the cutters are snapped upwardly by the spring 53 out of the path of the work-sheet, and the driver, as it continues its forward 5 movement, rotates the platen, line-spaces the work-sheets, and brings a new portion of the margins below the cutters. The ring 45 and flange 46 may be provided with an opening 61, through which the punchings may fall. 10 The cutting gages 40 may be operated independently of the line-spacing mechanism by means of a key 62 fixed to the rock shaft 43. When it is desired to operate the line-spacing mechanism, without operating the 15 cutting gages, a key 63 is depressed to silence the gages. This key (Figs. 2 and 10) is pivoted at 64 on the platen frame, and comprises a depending arm 65 provided at its lower end with an inclined cam face 66, 20 which, as the key is depressed, is swung forward and strikes a pin 67 on the arm 50, thereby swinging said arm downwardly to the Fig. 10 position, in which it is held below the driver 49, so that the line-space lever 25 may be operated without affecting the cutting gages. When the key 63 is fully depressed, the cam surface 66 is carried beyond the pin 67, so that the latter bears against a dwell surface 68. The key 63 is 30 held in either its depressed position or its normal inoperative position by a spring detent arm 69, having a detent to seat in notches 70 in the platen frame.

The gages 40 may also be actuated by the 35 platen-feed-roll release key 29. To this end, the arm 31 (Fig. 9) of the release key lever has fixed thereto an extension 71, provided with a cam surface 72, which, when the key 29 is depressed, strikes a pin 73 on a rock 40 arm 74 on the shaft 43, and rocks said shaft to swing the cutters to the Fig. 5 position. The pin 73 now rests against a dwell surface 75, thereby holding the gages 40 in operative 45 position until the key 29 is returned. It will be seen, by reference to Fig. 9, that the key 29 is depressed sufficiently to throw the feed rolls off the platen before the gages are operated. In other words, the feed rolls may be moved to and from the platen without 50 operating the gages.

Each cutter comprises a longitudinal cutting edge 76 (Fig. 9) and a transverse cutting edge 77 (see also Fig. 11). The latter edge at each cut forms the gaging edge or 55 shoulder 41 on the work-sheet. The cutting edges 76 and 77 are preferably both inclined so as to produce a shearing cut. The outer end face 78 of the cutter block is preferably curved in an arc concentric with the pivot 60 shaft 43, and, when the cutters are swung inwardly, provides a gage or abutment to which the sheets may be gaged, as herein-after pointed out. Guide plates 79 may be located below the gages 40 and extend within 65 a short distance of the gates, said guide

plates being spaced from the ring 45 to provide a guideway for the margins of the work-sheets. Said guide plates serve to hold the sheets close to the ring 45 at the gages, thus securing accuracy and uniformity of the 70 gaging operations.

Fig. 6 indicates a method of arranging and gaging a number of the work-sheets on the platen prior to typewriting thereon. These sheets *a*, *b* and *c* may all be placed 75 on the platen at the same time, and then individually adjusted and gaged on the platen by bringing the gaging shoulders 41 on the sheets up to the gages 40. That is, after the sheets have been placed on the platen, the 80 innermost sheet *a*, for example, may be grasped at its leading edge (either at the middle or at one or both corners) and drawn upwardly until the shoulders 41 thereof are brought up to the gages 40. The sheets *b* 85 and *c* may in turn be gaged in like manner. The sheets are thus collated and gaged so that each sheet is in proper position for receiving typewritten matter directly below the last line typewritten thereon before the 90 sheet was removed from the machine at a preceding operation. It will be understood that carbon sheets 80 are interposed between the several work-sheets *a*, *b* and *c*, and are narrower than the work-sheets, so that they 95 are not affected by the cutters.

Prior to placing the sheets on the platen as shown in Fig. 6, the feed-roll release key 29 may be depressed to the Fig. 5 position, thereby throwing the feed rolls off the 100 platen, enabling the sheets to be quickly placed on the machine without rotating the platen, the gages 40 by such depression of the key 29 being brought to operative position. When the sheets have been individually adjusted to the gages, as above noted, the release key 29 is lifted to return the feed rolls and clamp the work-sheets to the platen, and at the same time withdraw the gages to an inoperative position. The line-space lever is operated after the completion of each typewritten line, to advance the work-sheets and concomitantly operate the cutters. After the last line has been typewritten, the line-space lever may again be 115 operated before removing the sheets, to bring them to the position they will occupy when again placed on the machine and adjusted ready to be written upon. The key 29 may then be operated, before withdrawing the sheets, to lift the feed rolls and at the same time operate the cutting gages 40, so that when the sheets are again placed on the machine and adjusted to the gages, they are in position to be written upon without 120 operating the line-spacing lever.

The work-sheets, if desired, may be provided with rows of perforations 81, permitting marginal strips to be torn off, after the typewritten entries on the sheet have been 125

completed. The record sheets, as *a* and *b* may be provided with the usual perforations 82, for securing the sheets in loose-leaf ledgers or the like. As shown in Fig. 7, 5 work-sheets 83 may be manufactured with portions of their side edges cut away or formed to provide gaging edges 41 in such position that when the sheet is placed on the platen and adjusted to bring the edges 10 41 to the gages 40, the sheet is in proper position to receive the first typewritten matter. Such sheets may be printed bill-heads, invoice-sheets or other printed forms, or plain sheets.

15 The present invention is particularly useful in work wherein a number of sheets are placed together on the machine, with their leading edges at different positions of advancement, as is customary in some systems 20 of bookkeeping and in other work. Thus, for example, it is customary to place a record sheet, such as *b* (Fig. 6), together with an overlying or underlying bill or invoice, to receive typewritten entries. The record 25 sheet may receive the entries made on a number of different bills or invoices, so that said record sheet may be placed on the machine many times, and each time in a different position relatively to the accompanying bill 30 or invoice-sheet. The present invention permits all the sheets to be placed on the machine at once and quickly adjusted, to bring the individual sheets, each to a position corresponding to that of the last written line 35 thereon, without requiring the operator to see the typewritten matter on the sheet, which may be hidden by an overlying sheet.

The work-sheets may be manufactured 40 with gaging shoulders 41 as indicated in Fig. 7, in such position that when the sheet is gaged thereby on the machine, it will be in position to receive the first line of writing. The sheet may have a printed heading, including a date line as shown, which will 45 be positioned at the printing line on the platen when the sheet is gaged by means of said shoulders 41.

Although, for the purpose of construction, the cutting edges 76 and 77 are on the same 50 block that forms the gage, that is to say, the cutter and gage are formed of one piece, yet the function of the cutter is entirely distinct from that of the gage, and said elements do not need to be formed as a single 55 part in all cases. By curving the surface 78 of the gage concentrically with the pivot shaft 43, as before noted, the gaging surface serves to position the sheets at the precise 60 position they occupied when operated upon by the cutters, although this is not necessary in all cases, nor is it essential that the position to which the sheets will be gaged be the same as that occupied by the sheets when 65 operated upon by the cutters, nor that the cutters and gage be simultaneously operated.

Variations may be resorted to within the scope of the invention, and portions of the improvements may be used without others.

Having thus described my invention, I claim:

1. In a typewriting machine, the combination with a platen, and line-space mechanism therefor, of means operable repeatedly by said line-space mechanism to produce on a work-sheet, at one insertion thereof, and 75 while on the platen, a resultant gaging abutment by which the sheet, if removed from the machine and again placed thereon, may be adjusted to a position having a predetermined fixed relation to the position of the sheet at the time said gaging abutment was produced.

2. In a typewriting machine, the combination with a platen, and line-space mechanism therefor, of a sheet-gaging mechanism 85 comprising means operable repeatedly by said line-space mechanism on a work-sheet, at one insertion thereof, and while on the platen, to form a resultant sheet-gaging abutment on the sheet, and a gage on said typewriting machine to which said abutment may be brought to gage the sheet at a single predetermined position relative to that of the sheet at the time said abutment was formed.

3. In a typewriting machine, the combination with a platen, and line-space mechanism therefor, of a sheet-gaging and cutting device operable repeatedly by said line-space mechanism to form on a work-sheet, while 100 on the platen, a resultant gaging abutment by which the sheet, if removed from the machine and again placed thereon, may be adjusted to said device in a single position dependent upon the location of said abutment.

4. In a typewriting machine, the combination with a platen, and means for feeding a work-sheet over the platen, of sheet-gaging mechanism comprising a punching or cutting device operable, while the sheet is on the platen, to cut said sheet to form a gaging edge or shoulder thereon, said mechanism also providing a gage to which said edge may be brought to gage the sheet to a position having a predetermined fixed relation to the position of the sheet at the time said gaging edge was formed.

5. In a typewriting machine, the combination with a platen and means to feed work-sheets thereover, of sheet-cutting and gaging mechanism, comprising a gage and cutter operable to form on the margin of the work-sheet a gaging edge extending transversely of the direction in which the sheet is advanced over the platen, whereby said sheet, when removed from the platen and again placed thereon, may be advanced to cause said gaging edge to abut the gage, so that the sheet is positioned at a point of 130

- advancement determined by the position of the sheet at the time said gaging edge was formed thereon.
6. In a typewriting machine, the combination with a platen and means to feed work-sheets thereover, of a sheet-gaging punch operable to punch or cut a marginal portion of the work sheet and thereby produce a gaging edge, said punch also forming a gage to which said edge may be brought when the sheet has been removed and again placed on the platen, whereby the sheet is brought to a position determined by the position of the sheet at the time said punch was operated.
7. In a typewriting machine, the combination with a platen and means to feed work-sheets thereover, of a sheet-gaging punch operable to punch or cut a marginal portion of the work-sheet and thereby produce a gaging edge, said punch also forming a gage to which said edge may be brought when the sheet has been removed and again placed on the platen, whereby the sheet is brought to a position determined by the position of the sheet at the time said punch was operated, and means for moving said punch out of the path of the sheet to permit the sheet to be advanced beyond said gaging position.
8. In a typewriting machine, the combination with a platen, of means to advance work-sheets over the platen, types to print on said sheets, and gaging means operable repeatedly independently of the types to produce on the edge of the work-sheet a single resultant gaging impression by which the sheet, if removed from the platen and again placed thereon, may be gaged or adjusted to a position determined by the position of the last printed line on the sheet.
9. In a typewriting machine, the combination with a platen, of means to advance work-sheets over the platen, types to print on said sheets, gaging means operable independently of the types to produce on a work-sheet a gaging impression by which the sheet, if removed from the platen and again placed thereon, may be gaged or adjusted to a position determined by the position of the last printed line on the sheet, and means whereby said gaging means is operated and controlled by said sheet-advancing means.
10. In a typewriting machine, the combination with a platen and means to feed a work-sheet thereover, of a device operable concomitantly with the advancing of the sheet to trim or cut from the side edge of the sheet a length of strip proportional to the distance the sheet has been fed over the platen.
11. In a typewriting machine, the combination with a rotary platen, of line-spacing mechanism to rotate the platen step by step to feed a work-sheet thereover, and means coöperating with said line-spacing mechanism to trim a progressively lengthening strip from the side margin of the work-sheet step by step as the line-spacing mechanism is operated, thereby advancing at each line-spacing operation a resultant sheet-gaging shoulder or edge by which the sheet can be adjusted or gaged on the platen to a position having a fixed relation to the position of the sheet at the last operation of said trimming means.
12. In a typewriting machine, the combination with a rotary platen, of line-spacing mechanism to rotate the platen step by step to feed a work-sheet thereover, means coöperating with said line-spacing mechanism to trim a progressively lengthening strip from the side margin of the work-sheet step by step as the line-spacing mechanism is operated, thereby advancing at each line-spacing operation a sheet-gaging shoulder or edge, and a gage on said typewriting machine to which said edge may be adjusted.
13. In a typewriting machine, a combination with a rotary platen, of line-spacing mechanism to rotate the platen step by step to feed a work-sheet thereover, means coöperating with said line-spacing mechanism to trim a strip from the side margin of the work-sheet step by step as the line-spacing mechanism is operated, thereby providing at each line-spacing operation a sheet-gaging shoulder or edge, and a gage forming an abutment to which said edge may be adjusted, said gage positioned to gage the sheet at the position occupied when said edge was formed.
14. In a typewriting machine, the combination with a rotary platen and means to feed a work-sheet thereover, of a sheet-cutting or punching device at the end of the platen, said cutting device including means operable to cut or punch a portion of the work-sheet projecting beyond the end of the platen, to thereby advance a single gaging edge or shoulder gradually to a position along the margin of the work-sheet corresponding with the position of advancement of said sheet over the platen at the time said device is operated.
15. In a typewriting machine, the combination with a rotary platen, of a sheet-cutting die, a stationary die block at the end of the platen over which the margin of a work-sheet may project as it is fed over the platen, and means to operate said die to cut or punch said projecting portion of the work-sheet at a point along the side margin corresponding with the position of advancement of the sheet over the platen.
16. In a typewriting machine, the combination with a roller platen, and a line-spacing mechanism, of a cutter at one end of the platen, and means controlled by said line-spacing mechanism to operate said cutter,

5 said operating means including means to cause said cutter to cut or punch the margin of a work-sheet when the latter is on the platen with said margin projecting beyond the end of the platen.

17. In a typewriting machine, the combination with a roller platen, of a rock shaft extending lengthwise of the platen, rock arms secured to said shaft at opposite ends 10 of the platen, cutters on said rock arms, and means to rock said shaft and swing the cutters toward and from the platen axle and thereby cause them to cut or punch the side margins of a work-sheet on the platen with 15 said margins projecting beyond the platen ends.

18. In a typewriting machine, the combination with a roller platen, of a rock shaft extending lengthwise of the platen, rock 20 arms secured to said shaft at opposite ends of the platen, cutters on said rock arms, means to rock said shaft and swing the cutters toward and from the platen axle and thereby cause them to cut or punch the side 25 margins of a work-sheet on the platen with said margins projecting beyond the platen ends, line-spacing mechanism operable to rotate the platen step by step, and a connection between said mechanism and the means for 30 operating the cutters whereby the latter are operated at each line-spacing operation.

19. In a typewriting machine, the combination with a roller platen, of a rock shaft extending lengthwise of the platen, rock 35 arms secured to said shaft at opposite ends of the platen, cutters on said rock arms, means to rock said shaft and swing the cutters toward and from the platen axle and thereby cause them to cut or punch the side 40 margins of a work-sheet on the platen with said margins projecting beyond the platen ends, line-spacing mechanism operable to rotate the platen step by step, a connection between said mechanism and the means for 45 operating the cutters whereby the latter are operated at each line-spacing operation, and means to silence said cutters and permit the line-spacing mechanism to be operated independently thereof.

50 20. In a typewriting machine, the combination with a roller platen and platen frame, of a die block on the platen frame at the end of the platen, said block having a curved surface forming a continuation of the 55 curved platen surface, said block having a die opening, and a sheet-cutting die arranged to swing toward and from the die block at said opening for cutting or punching the margin of a work-sheet on the platen 60 when said margin projects beyond the platen onto said surface.

21. In a typewriting machine, the combination with a roller platen and platen frame, of a die block on the platen frame at the 65 end of the platen, said block having a curved

surface forming a continuation of the curved platen surface, said block having a die opening, a sheet-cutting die arranged to swing toward and from the die block at said opening for cutting or punching the margin 70 of a work-sheet on the platen when said margin projects beyond the platen onto said surface, and means to rotatably adjust said die block to adjust the die opening to the die.

22. In a typewriting machine, the combination with a platen frame and a roller platen journaled therein, of an annular support on said frame interposed between the frame end and the end of the platen, a ring mounted on said support, said ring being 75 concentric with the platen and of the same diameter as the platen to form a supporting surface for the projecting margin of a work sheet on the platen, said ring formed with a die opening, and a die or cutter arranged to swing toward and from said ring to cut or punch said margin of the work sheet, and means to rotatably adjust said ring on said support to accurately aline or adjust the die 80 opening to the die. 90

23. In a typewriting machine, the combination with a rotary platen, of line spacing mechanism to rotate the platen, and a gaging device operated by said mechanism at each line spacing operation to produce on a 95 work sheet on the platen, an impression by means of which the sheet may thereafter be gaged.

24. In a typewriting machine, the combination with a rotary platen, of line spacing 100 mechanism to rotate the platen, a gaging device operated by said mechanism at each line spacing operation to produce on a work sheet on the platen, an impression by means of which the sheet may thereafter be gaged, 105 and means for silencing said gaging device to permit the line spacing mechanism to be operated independently thereof.

25. In a typewriting machine, the combination with a rotary platen, of line spacing 110 mechanism to rotate the platen, a gaging device operated by said mechanism at each line spacing operation to produce on a work sheet on the platen, an impression by means of which the sheet may thereafter be gaged. 115 and means to operate said gaging device independently of the line spacing mechanism.

26. In a typewriting machine, the combination with a rotary platen, of line spacing 120 mechanism to rotate the platen, a gaging device operated by said mechanism at each line spacing operation to produce on a work sheet on the platen, an impression by means of which the sheet may thereafter be gaged, 125 means for silencing said gaging device to permit the line-spacing mechanism to be operated independently thereof, and means to operate said gaging device independently of the line-spacing mechanism.

27. In a typewriting machine, the combi- 130

nation with a rotary platen, of line-spacing mechanism including a lever operable to rotate the platen, said lever having an initial idle movement during which the platen remains at rest, an impression device operable to produce a gaging impression on a work-sheet on the platen, and operating connections between said lever and said device, operable to actuate the latter during the said 10 idle movement of said lever.

28. In a typewriting machine, the combination with a rotary platen, of line-spacing mechanism to rotate the platen, said mechanism including a line-spacing lever having 15 a limited idle movement during which the platen remains at rest, said lever operable during the remainder of its movement to rotate the platen, a cutter arranged to swing toward and from the platen for cutting or 20 punching the margin of a work-sheet at each operation, and means whereby said lever during said idle movement is operative to swing the cutter to cutting position and then cause the cutter to be withdrawn before the 25 platen is rotated by the line-spacing lever.

29. In a typewriting machine, the combination with a rotary platen, of line-spacing mechanism comprising a line-spacing lever and a driver actuated thereby, said driver 30 having an initial movement during which the platen remains at rest, the platen being rotated by said driver during the continued movement of the driver, a cutter mounted to swing toward and from a work-sheet on the 35 platen for cutting or punching the latter, means to operate said cutter, comprising an arm in the path of said platen driver and operable by the latter during said initial movement to swing the cutter to operative 40 position, means to release the cutter from said driver before the platen is rotated, and means to automatically throw the cutter out of the path of the work-sheet when so released, permitting the work-sheet to be ad- 45 vanced when the platen is rotated.

30. In a typewriting machine, the combination with a rotary platen, of line-spacing mechanism comprising a line-spacing lever and a driver actuated thereby, said driver 50 having an initial movement during which the platen remains at rest, the platen being rotated by said driver during the continued movement of the driver, a cutter mounted to swing toward and from a work-sheet on 55 the platen for cutting or punching the latter, means to operate said cutter, comprising an arm in the path of said platen driver and operable by the latter during said initial movement to swing the cutter to operative 60 position, means to release the cutter from said driver before the platen is rotated, and means to automatically throw the cutter out of the path of the work-sheet when so released, permitting the work-sheet to be ad- 65 vanced when the platen is rotated, and means

to operate said cutter independently of the line-spacing mechanism.

31. In a typewriting machine, the combination with a rotary platen, of line-spacing mechanism comprising a line-spacing lever 70 and a driver actuated thereby, said driver having an initial movement during which the platen remains at rest, the platen being rotated by said driver during the continued movement of the driver, a cutter mounted 75 to swing toward and from a work-sheet on the platen for cutting or punching the latter, means to operate said cutter, comprising an arm in the path of said platen driver and operable by the latter during said initial 80 movement to swing the cutter to operative position, means to release the cutter from said driver before the platen is rotated, means to automatically throw the cutter out of the path of the work-sheet, when so released, permitting the work-sheet to be ad- 85 vanced when the platen is rotated, feed rolls running on the platen and coöperating therewith to feed the work-sheet, a key to release said feed rolls, and means operated by said 90 key to actuate said cutter.

32. In a typewriting machine, the combination with a rotary platen, of line-spacing mechanism comprising a line-spacing lever and a driver actuated thereby, said driver 95 having an initial movement during which the platen remains at rest, the platen being rotated by said driver during the continued movement of the driver, a cutter mounted to swing toward and from a work-sheet on 100 the platen for cutting or punching the latter, means to operate said cutter, comprising an arm in the path of said platen driver and operable by the latter during said initial movement to swing the cutter to operative 105 position, means to release the cutter from said driver before the platen is rotated, means to automatically throw the cutter out of the path of the work-sheet when so released, permitting the work-sheet to be ad- 110 vanced when the platen is rotated, feed rolls running on the platen and coöperating therewith to feed the work-sheet, and a key to release said feed rolls, said key operable when moved to position to throw the feed 115 rolls off the platen, to also move the cutter to operative position, said cutter when in said operative position arranged to form a gage to which the work-sheet may be adjusted.

33. In a typewriting machine, the combination with a roller platen, of means to hold a work-sheet thereon, a key operable in one direction to release said means to permit work-sheets to be removed from or placed 125 on the platen, said key operable, when returned, to clamp the sheets to the platen, and a device operable by said key to produce an impression on a work-sheet by means of which said sheet, after removal from the 130

platen, may be again adjusted on the platen to a position determined by its position at the time said impression was made thereon.

34. In a typewriting machine, the combination with a rotary platen, of platen feed rolls bearing against the platen and coöperating therewith to feed a work-sheet over the platen, a key to release said rolls, and a cutter operable by said key to cut the side margin of the work-sheet at a point corresponding to the position of advancement of said sheet at the time the cutter was operated, thereby producing a shoulder or gaging edge by which the sheet may later be

15 adjusted to a gage.

35. In a typewriting machine, the combination with a rotary platen, of platen-feed rolls, a feed-roll-release key operable to throw said rolls off the platen, a device for 20 cutting or punching the margin of a work-sheet while the latter is on the platen, to form a gaging edge or shoulder on the work-sheet, and connections from said key to said device for operating the latter when the key 25 is fully depressed, said key operable by a movement to an intermediate position to cast off the feed rolls without operating said device.

36. In a typewriting machine, the combination 30 of a platen, sheet-feeding means, and means operable repeatedly at a single insertion of the sheet, to advance on a work-sheet, while on the platen, a single sheet-gaging abutment at the side margin of the 35 sheet.

37. In a typewriting machine, the combination 40 of a device to simultaneously form sheet-gaging abutments on a number of work-sheets on the machine, said device also forming a gaging stop to which the sheets may be individually adjusted, each to bring its said abutment against the stop, to thereby bring the several sheets in register at the same relative position occupied by said 45 sheets when the said abutments were formed.

38. In a typewriting machine, the combination of a revoluble platen, and means at the delivery side of the platen and close to the printing line on said platen for guiding a work-sheet into position thereon, said 50 means comprising gages between which the sheet may be guided during the line-spacing operations, and by which the position of the sheet lengthwise of the platen is determined, said gages also forming abutments against 55 which transverse edges or shoulders on the margins of the work-sheet may be brought to gage the initial position of the sheet circumferentially of the platen.

39. The combination with a regulatable 60 line-spacing mechanism, of means capable of punching out the side edges of the work-sheet for all line-space movements controlled by such regulation, to make a single continuous cut along each edge, and thereby form 65 resultant opposite gaging abutments in the sheet.

40. In a typewriting machine, the combination of a revoluble platen, means at the delivery side of the platen and near the 70 printing line for guiding a work-sheet into position thereon, said means comprising gages between which the sheet may be guided, and by which the position of the sheet lengthwise of the platen is determined, said 75 gages being movable into and out of gaging position and capable of serving as abutments against which transverse edges or shoulders on the margins of the work-sheet may be brought to gage the position of the 80 sheet circumferentially of the platen, and means for withdrawing said gages from the path of the sheet, to permit it to be advanced beyond said gaged position, and for restoring said gages to normal position.
